W. M. PATTERSON,
PICKER STICK CHECK.
APPLICATION FILED DEC. 1, 1921.

1,417,557.

Patented May 30, 1922.

UNITED STATES PATENT OFFICE.

WILLIAM M. PATTERSON, OF GREENVILLE, SOUTH CAROLINA.

PICKER-STICK CHECK.

1,417,557.

Specification of Letters Patent. Patented May 30, 1922.

Application filed December 1, 1921. Serial No. 519,151.

To all whom it may concern:

Be it known that I, WILLIAM M. PATTERSON, a citizen of the United States of America, and a resident of Greenville, county of Greenville and State of South Carolina, have invented certain new and useful Improvements in Picker-Stick Checks, of which the following is a full and clear specification.

10 The object of this invention is to greatly reduce the length of strap required to make the check loop, thereby greatly saving in leather and also, and most important, enabling me to utilize parts of comparatively 15 long worn-out check-straps of the type now in use, as more fully hereinafter set forth.

In the drawing—

Fig. 1 is a side elevation partly in section of a device embodying my invention;

20 Fig. 2 is a plan view thereof;

Fig. 3 is a side elevation of a modified form of check-strap support;

25 Figs. 4, 5 and 6 are detail views showing a modified form of support for the strap.

30 In the drawing, 5 designates a hanger of the usual construction which depends from the lay, and attached to one face of this hanger is a pair of arms 6 extending in opposite directions and lying parallel with the lay, the outer, free end of each arm being bent up to vertical position to form a vertical pivot 7. The leather strap 8 has its ends 35 respectively pivotally connected to said pivots by means of leather clamps 9, each of these clamps consisting of a short piece of leather folded around the pivot and secured to the end of the strap by means of a bolt 10, a bushing of fibre 11 being employed between the metal pivot 7 and the strap 9 to

40 prevent undue wear of the strap. The end of the check-strap abuts the bushing 11 to thereby make a snug fit around the bushing.

The check-strap 8 is sufficiently greater in length than the distance between the two 45 pivots 7 to provide sufficient fullness at one side of the supporting arms 6 to form a loop in which the picker-stick 12 works, being arrested at each end of its stroke by the looped end of the strap, as shown in Fig. 2. It will 50 be observed that with my construction the leather strap 8 may be no more than approximately half the length of the usual all-leather strap now in general use and that, therefore, I may construct my check from 55 parts of worn-out straps of the old type, thereby enabling me to use the old worn-out

straps which have heretofore been discarded as waste.

In Fig. 3 it will be observed that the pivots 7 are extended and bent inwardly far enough to lie against the hanger, thereby forming arms 13 which assist the arms 6 in rigidly supporting pivots 7. The ends of the arms 6 and 13 are rigidly but removably secured to the hanger by means of a clamp-block 14 which is bolted to the hanger by means of the bolt 15.

In Figs. 4, 5 and 6 I illustrate one of the many modified arrangements I may adopt for supporting or suspending the pivots 7.

70 In this case, the pivots consist of bolts 7' depending from a bracket 16 affixed to the lay. Two bolts and two brackets are of course employed. Each bolt is provided with a head 17 at its lower end, and the two bolts are connected by a horizontal bar 18. For adjustment purposes, the horizontal members of the bracket 16 are each provided with a series of bolt-holes 19. The upper end of the pivot-bolt 7' is shouldered so as 80 to fit solidly against the underside of the bracket, a nut 20 being screwed on the upper end of the bolt for the purpose of securing it rigidly in the selected hole 19.

The nature and scope of the invention 85 having been thus indicated and its preferred embodiment having been specifically described, what is claimed as new is:

1. A picker-stick check consisting of a pair of vertical pivots and means for attaching them underneath the lay at one side thereof, and a flexible check-strap having its ends pivotally connected to said pivots, said pivots being set apart sufficiently far to prevent side-pull on the check-strap. 95

2. A picker-stick check embodying a hanger depending from the lay, a pair of oppositely-extending independently adjustable arms attached to the hanger and each having a vertical pivot, and a flexible strap having its ends pivotally attached to the respective pivots. 100

3. A picker-stick check consisting of a pair of vertical pivots and means for attaching them underneath the lay, and a flexible check-strap having its ends pivotally connected to said pivots, the connection to the pivots being made by means of strap-clamps secured to the strap and surrounding the pivots. 105

4. A picker-stick check consisting of a pair of vertical pivots and means for at- 110

taching them underneath the lay, and a flexible check-strap having its ends pivotally connected to said pivots, the connection to the pivots being made by means of leather strap-clamps secured to the strap and surrounding the pivots, a fibre bushing being arranged between the pivot and the strap-clamp.

5. A picker-stick check consisting of a pair of vertical pivots and means for attaching them underneath the lay at one side thereof and at a distance apart, and a flexible check strap having its ends pivotally connected to said pivots.

6. A picker-stick check consisting of a 15 pair of vertical pivots and means for attaching them underneath the lay at one side thereof and at a distance apart, said means embodying devices permitting said distance to be varied, and a flexible check-strap 20 having its ends pivotally connected to said pivots to thereby permit the end-portions of the strap to swing freely laterally on said pivots.

In testimony whereof I hereunto affix my 25 signature.

WILLIAM M. PATTERSON.
